MULTIPLE COIN CONTROLLED MECHANISM

Wilhelm Wellstein, Detroit, Mich., assignor to
Ex-Cell-O Corporation, Detroit, Mich., a corporation of Michigan

Application October 22, 1947, Serial No. 781,321

7 Claims. (Cl. 194—10)

1

The present invention relates generally to coin controlled devices and more specifically to a multiple coin controlled release mechanism which is well adapted for use in installations where purchase money, transportation fares, admission fees and the like must be collected without the personal supervision of an attendant or cashier.

One of the objects of the invention is to provide a multiple coin controlled releasing mechanism which will be responsive to the depositing in any sequence of coinage aggregating a predetermined total value. This comprehends responsiveness to the deposit of all possible combinations of coins in the denominational series falling within such predetermined total value.

Another object is to provide a multiple coin controlled mechanism of the character set forth and in which provision is made for adjustment to selectively establish the predetermined total value of coinage to which the device responds.

A further object is to provide a coin controlled mechanism of the above type wherein coins deposited in excess of the predetermined total value for which the mechanism has been set will be immediately and automatically returned to the customer.

Still another object is to provide a coin controlled mechanism of the character set forth wherein coinage totaling to the predetermined value or to a lesser value may be returned at the option of the depositor at any time before he starts to claim his purchase. A related object is to provide a mechanism of the above type wherein coins deposited prior to the deposit of a defective or spurious coin will be returnable, together with the defective coin.

Further objects and advantages will become apparent as the following description proceeds, taken in connection with the accompanying drawings in which:

Figure 1 is a fragmentary vertical sectional view through the front portion of the cabinet of a vending machine in which the illustrative embodiment of the invention has been utilized, the coin controlled mechanism being shown in side elevation.

Fig. 2 is a fragmentary front elevational view of the coin controlled mechanism shown in Fig. 1.

Fig. 3 is an enlarged fragmentary rear elevational view of certain external members associated with the coin controlled mechanism shown in Fig. 1.

Fig. 4 is an enlarged fragmentary transverse sectional view through the coin mechanism il-

lustrated in Fig. 1 and taken in the plane of the line 4—4.

Fig. 5 is an enlarged fragmentary vertical sectional view taken longitudinally through one of the penny accumulating chutes and in the plane of the line 5—5 of Fig. 4.

Fig. 6 is a view similar to that shown in Fig. 5 but taken through another one of the penny accumulating chutes and in the plane of the line 6—6 of Fig. 4.

Fig. 7 is an enlarged fragmentary vertical sectional view taken longitudinally through the nickel accumulating chute and in the plane of the line 7—7 of Fig. 4.

Fig. 8 is an enlarged fragmentary vertical sectional view taken longitudinally through the dime accumulating chute and in the plane of the line 8—8 of Fig. 4.

Fig. 9 is an enlarged fragmentary vertical sectional view through the coin diverting gate of the mechanism shown in Fig. 2 and taken in the plane of the line 9—9.

Fig. 10 is an enlarged fragmentary sectional view through the coin return interlock of the mechanism illustrated in Fig. 1 and taken in the plane of the line 10—10.

Fig. 11 is an end elevation of the penny director of the coin controlled mechanism embodying the invention and showing the relationship of such director to the weight biased dogs associated therewith.

Fig. 12 is an enlarged fragmentary plan view of the horizontally rockable floating lever and certain adjacent parts of the foregoing coin controlled mechanism.

Fig. 13 is an enlarged plan view of the coin actuated stop dogs associated with the slidable master gate.

Fig. 14 is an enlarged fragmentary perspective view of the mechanically coupled coin diverters associated with the nickel and dime accumulating chutes.

Figs. 15 and 18, inclusive, are plan views of the slidable master gate in its various positions with respect to the coin accumulating chutes, the relative locations of the latter and the floating lever being indicated by dot dash lines.

Figs. 19 to 23, inclusive, are schematic line diagrams illustrating the relationship between the various step-by-step movements of the principal movable members comprising the coin counting means.

While the invention is susceptible of various modifications and alternative constructions, a preferred embodiment has been shown in the

drawings and will be herein described in some detail, but it is to be understood that there is no intention to limit the invention to the specific form disclosed, the intention being, on the contrary, to cover all modifications and alternative constructions falling within the spirit and scope of the invention as expressed in the appended claims.

Referring to the drawings more specifically, an exemplary embodiment of the invention has been there illustrated in the form of a coin controlled release mechanism 20 for a vending machine 21 although it will doubtless be appreciated that the invention is susceptible of utilization in many other applications. In the present instance, the illustrative vending machine 21 is of the type covered by Patent No. 2,425,870 to Charles H. Dixon, issued on August 19, 1947. Such a machine generally comprises a cabinet having a number of inclined chutes for storing articles of merchandise and loading the same by gravity into a number of liftable delivery receptacles associated with the chutes. For regulating the upward movements of the delivery receptacles, the same are equipped with individual guide rods 22 unitary therewith. The receptacles are normally retained in a locked condition, such being accomplished by means of a cam shaft 24 having a series of axially spaced locking cams 25 adapted to engage respective locking grooves 26 in the guide rods 22. If, however, the shaft 24 be rotated through a sufficient angle the cams 25 will be swung clear of the locking grooves 26 and any selected delivery receptacle may then be elevated for removal of a purchased article. The lifting of more than one delivery receptacle at a time is effectively precluded through the use of a ball interlock arrangement 28 associated with the rods 22, the details of the former being unimportant for present purposes.

Provision is made within the mechanism 20 for accumulating deposited coins until a predetermined total value thereof has been reached. This results in the closing of a switch 29 associated with the mechanism 20, the former in turn serving to energize an electrical control circuit which unlocks the article delivery receptacles for elevation of any selected one of the latter. Also associated with the mechanism 20 is a solenoid 30 which is adapted to be energized by another circuit as an incident to the elevation of such selected receptacle for delivery of a purchased article. By the use of an appropriate connecting linkage between the movable core 31 of the solenoid 30 and the mechanism 20, the coinage accumulated therein is dropped into a coin box 32 as soon as the solenoid is energized. The latter becomes deenergized upon the return of the elevated delivery receptacle to its lowermost position.

GENERAL ORGANIZATION OF COIN CONTROLLED RELEASE MECHANISM

The coin controlled mechanism 20 (refer to Figs. 1, 2 and 4) is assembled upon an open, box-like main frame 34 adapted to be mounted in a substantially upright position within the cabinet of the vending machine 21. Located in the cabinet wall and above the mechanism 20 are a series of coin slots 35, 36 and 38 which in the present instance are dimensioned for receiving pennies, nickels and dimes, respectively. Rigidly supported upon the frame 34 of the mechanism are a corresponding number of coin entry chutes 35a, 36a and 38a each adapted to register with a re-

spective one of the coin slots. Closely associated with the lower ends of the entry chutes and arranged to receive coins from the same are a corresponding number of coin selectors 35b, 36b and 38b. The latter merely serve to detect and retain defective or spurious coins such as magnetic slugs, eventually releasing and diverting them to a coin return channel. The coin selectors may be of any well known construction and their details form no part of the present invention. Mounted in the frame 34 below the coin selectors and arranged to receive coins from respective ones of the same are a plurality of accumulating chutes 35c1, 35c2, 35c3, 36c and 38c. The first three of these comprise a triplicate assembly for holding coins of the lowest denomination in the series of coinage usable in the mechanism, such denomination in the present case constituting pennies. The remaining accumulating chutes 36c and 38c are designed for the two next higher denominations which in this case are nickels and dimes. For the twofold purpose of controlling the actuation of the releasing switch 29 and the transfer of coinage from the accumulating chutes to the coin box 32, a novel step-by-step counting system is utilized. Such system is, of course, responsive to the various combinations and sequences of coins deposited in the mechanism 20. Also incorporated into the latter is a manual coin return arrangement operable in response to the depression of a coin return plunger 39 mounted on the cabinet wall.

COIN ACCUMULATING MEANS

The coin accumulating means, shown in detail in Figs. 4 through 8, comprises the accumulating chutes 35c1, 35c2, 35c3, 36c and 38c, already mentioned. The first three of these, being the penny chutes, are formed by a group of spaced-apart, parallel plates 40 of shallow channel-like cross section stacked successively against a flat outside plate 41. Each of the three thin rectangular compartments defined by this arrangement is subdivided into a pair of branch chutes by means of a vertically disposed central dividing partition 42.

In the present instance, the individual accumulating capacity of the chutes 35c2 and 35c3 is determined by certain coin-responsive devices and remains fixed at five pennies each. As indicated in Fig. 6, which is typical of both chutes, the first four pennies are directed into the left-hand branch chute, so as to fill the same. The topmost penny in the latter branch chute cooperates with the downwardly inclining upper end of the partition 42 to cause the fifth penny to spill over into the second branch chute.

The accumulating capacity of the chute 35c1, like that of the other two penny chutes is also determined by certain coin-responsive devices. The chute 35c1 can, however, be adjusted for an accumulating capacity of between one and four pennies. Such adjustment may conveniently be accomplished by the use of a hinged plate 44 (see Figs. 4 and 15 to 18) swingably mounted upon a vertical axis a short distance from the plate 40 constituting the chute side wall and biased into abutment therewith by appropriate resilient means. The plate 44 is formed with a series of tapped holes 45 spaced at a vertical interval approximately equal to the diameter of a penny. Stop screw 46 may be selectively threaded into any one of the tapped holes 45 and allowed to project across the first branch of the chute 35c1 by registering with one of a series of vertically spaced

holes 48 in the plate 40. In the illustrative mechanism, the screw 46 is located so as to project through the lowermost of the holes 48 and into the chute 35c1, giving the latter a total capacity of four instead of five pennies. As indicated in Fig. 5, the first three pennies will fill up the first branch of the chute 35c1 while the fourth penny will spill over into the second branch thereof.

For the purpose of channeling the proper number of pennies into each of the penny accumulating chutes, a penny director 49 is associated therewith. The director 49 comprises an L-shaped member journaled on a fixed support as at 50 for limited rocking movement about a horizontal axis lying parallel with the general planes of the penny chutes 35c1, 35c2 and 35c3. One leg of the penny director extends horizontally so as to overlie the penny chutes, being formed with a funnel-like converging passageway 51 which is adapted to receive pennies from the coin selector 35b and to guide them selectively into the underlying first branches of each of the penny accumulating chutes.

The nickel chute 36c is fashioned after the manner utilized in the construction of the penny chutes, being defined between a pair of spaced-apart parallel plates 52. The space enclosed between the latter is divided into first and second branch chutes by means of a vertical partition strip 54 similar to the strips 42. The accumulating capacity of the chute 36c, like that of the penny accumulating chutes, is determined by appropriate coin actuated devices and while such capacity could theoretically be higher, the chute 36c is arranged to accumulate up to two nickels, one in each branch thereof.

The dime chute 38c, like the other chutes, is defined between a pair of spaced-apart parallel plates 55. However, the dime chute only has a single accumulating branch which lies between a relatively wide border strip 56 and an interrupted border strip 58.

As indicated in Fig. 4, all of the foregoing coin chutes are assembled as a rigid unit together with a pair of spacer blocks 59 and 60, such assembly being bodily installed in the box frame of the coin controlled mechanism 20.

Closure means for preventing the flow of coins from the open bottom ends of the accumulating chutes is provided in the form of a master gate 61 which is retained in slidable abutment with the chute ends through the use of a pair of brackets 62 and 64 carried by the spacer blocks 59 and 60. Upon closer inspection of Figs. 5 through 8 and 15 through 18, it will be noted that the gate 61 is fashioned with a plurality of laterally projecting ears of various longitudinal dimensions and which serve as releasable stops for the coins in the overlying accumulating chutes.

COIN COUNTING SYSTEM

It will be helpful to a clearer understanding of the counting system to point out that its ultimate function is the closing of the releasing switch 29 immediately upon the accumulation of coinage in an amount equal to the predetermined total value for which the mechanism 20 has been conditioned to respond. Since such total may be reached by a number of coin combinations and subcombinations received in various sequences, a multiple step arrangement is utilized for the counting of the coins prior to the actuation of the switch 29. Turning now to Figs. 1 to 3, it will be noted that the switch 29 is provided with a resilient actuating arm 65. Operatively asso-

ciated with the switch arm 65 and adapted to cam into engagement therewith is a control member in the form of an upstanding crank arm 66. The latter is keyed or otherwise rigidly secured to a rockshaft 68 journaled in spaced-apart brackets 69 carried by the frame 34 of the mechanism. A tensile spring 70 disposed between the frame 34 and a pin unitary with the crank arm 66 exerts a constant biasing force tending to cam the crank arm 66 and the switch arm 65 together so as to close the switch 29. Keyed or otherwise fixed to the rockshaft 68 at a point intermediate the brackets 69 is another upstanding crank arm 71, the uppermost end of the same being bifurcated and equipped with adjustable trunnions 72 for receiving therebetween a horizontally rockable floating lever 74. The point of support for the latter is at its approximate geometrical center, the trunnions 72 being adapted to permit sliding engagement between themselves and a pair of concave recesses 75 formed in the sides of the lever. Pivotaly attached to one end of the lever 74 as by means of a pin 76 is the horizontally projecting outer end of the slidable master gate 61 associated with the coin accumulating tubes. Pivotaly attached as at 78 to the opposite end of the lever 74 is a simple twisted link 79 which connects the former with the depending extremity of the penny director 49. It will readily be appreciated upon more specific reference to Figs. 1 to 3 and to Fig. 12 that the biasing force of the tensile spring 70 will continuously tend to rock the crank arm 71 toward the mechanism 20. By the same token, it will be appreciated that any horizontal shifting to the left (as viewed in Fig. 12) of either the slide 61 or the depending end of the penny director 49 will be accompanied by a corresponding increment of arcuate movement of the crank 71 toward the mechanism 20. Coextensive with such movement of the crank 71 is an arcuate increment of movement of the crank arm 66 toward the switch closing position.

In the present instance the counting mechanism for the lever 71, together with the rockshaft 68 and crank arm 66, must travel through three approximately equal steps or increments of arcuate movement in order to close the switch 29. Such steps may be derived from corresponding increments of movement by the master gate 61 with the connection 78 between the floating lever 74 and the lower end of the penny director 49 serving as a fixed fulcrum. Conversely, these steps may be derived from corresponding increments of movement of the lower end of the penny director with the connecting point 76 between the lever 74 and the gate 61 serving as the fulcrum. Accordingly, there is provided means responsive to the presence of various coin combinations in the accumulating chutes for imparting step-by-step movements to the gate 61 and to the penny director 49.

Considering first the penny director 49, it will be noted that the same is fashioned with an extending arm 80 substantially perpendicular to the plane thereof and projecting through one side of the frame 34 of the mechanism 20. Pivotaly carried by means of fixed supporting brackets 81 and located slightly below the arm 80 are three weight-biased, disengageable stop dogs 82, 83 and 84 of unequal radial lengths. Each of these dogs has a unitary tail bar adapted to extend across aligned slots in one or more of the penny accumulating chutes 35c1, 35c2, and 35c3, the upper edges of such slots serving to limit the tendency of the tail bars to swing upwardly under the action of

the dog biasing weights. With this arrangement, the interception by the respective tail bars of coins in the penny chutes serves to successively disengage the dogs 82, 83 and 84 from the arm 80, thus permitting the penny director 49 to swing through three successive increments of movement.

Turning now to the slideable master gate 61 (refer to Figs. 4 and 13), a pair of successively engageable, weighted stop dogs 85 and 86 are associated therewith. These dogs are fashioned with relatively short tail bars extending transversely across the nickel accumulating chute 36c and through slots in the side wall 52 thereof. As the tail bars are depressed successively by the interception of coins in the nickel chute, the stop dogs 85 and 86 are successively lifted out of engagement with the abutments of the gate 61, thus providing two increments of sliding movement for the latter. Closely associated with the nickel dogs 85 and 86 is a simple pivotal lever 88, one arm of which constitutes a tail bar and extends across the dime accumulating chute 38c. The depression of this bar results in the simultaneous disengagement of both dogs 85 and 86, thus creating an alternative means of obtaining the movement increments otherwise obtainable with the nickel dogs 85 and 86 actuated separately. It might be noted in passing that the extreme left-hand limit of sliding movement of the master gate 61 is determined by abutment between a depending pin 89 thereon and the right-hand edge of the supporting bracket 64.

In order that coinage deposited in the mechanism 20 may be accumulated in workable combinations, there is operatively associated with the step-by-step counting system a coin diverting device for each of the accumulating chutes. Thus the diversion of coins from the penny accumulating chutes, required for example when the passage 51 of the penny director 49 is out of registration with such chutes, is accomplished by the use of a downwardly inclined, wedge-shaped lug 99 unitary with the leg of the director 49 overlying the chutes (see Figs. 2, 4 and 11). The sloping surface of the lug 99, and which may be somewhat concave, serves to direct coins from the coin selector 35b to a spilling chute 91. The latter drops them down along the front of the mechanism 20 and into a dumping chamber 92, shown in detail in Fig. 9. This chamber can be arranged for communication with either the coin return tray 94 of the mechanism 20 or the coin box 32 thereof, depending upon the position of a swingable dumping gate 95. The latter occupies a normally open position with respect to the coin return tray 94, thus allowing diverted coins to pass from the dumping chamber 92 to the tray 94 for return to the customer.

The coin diverting means for the nickel and dime accumulating chutes 36c and 38c comprises a pair of rockably mounted levers 96 and 98 mechanically connected together as by a link 99 (see Figs. 4, 7, 8 and 14). The upstanding end of the lever 96, associated with the nickel chute, is bifurcated and terminates in a pair of bent over portions 100 and 101 of unequal length. The upstanding end of the lever 98, associated with the dime chute, terminates in a single bent over portion 102. Both levers are biased toward a disengaged position with respect to the coin chutes by means of a coil spring 104. Unitary with the arm 96 is a depending finger 105 adapted to engage an abutment on the slideable master gate 61. Engagement between these parts

will occur as an incident to the leftward sliding movement of the gate 61, rocking the levers 96 and 98 against the action of the spring 104 and bringing the bent over portions 100, 101 and 102 into registration with appropriate slots 106 in the side walls of the chutes 36c and 38c. Coins diverted from these chutes are spilled laterally out of the same, thence dropping into the dumping chamber 92 and passing from there to the coin return tray 94.

COIN RETURN MEANS

From the time a customer deposits his first coin in the mechanism 20 up to the time he lifts a dispensing receptacle to claim his purchase, a return of the deposited coins can be had by simply depressing the coin return plunger 39. Even in the event that the normal depositing of coins is interrupted by the deposit of a spurious coin, a return of any and all coins so deposited can still be had. Thus there is provided a coin return lever 107 carried by a rockshaft 108 journaled at the top of the frame 34 of the mechanism 20 (see Figs. 1, 2 and 4). The upper end of the lever 107 extends into the path of the coin return plunger 39 for actuation thereby. The opposite end of the lever 107 has dependably connected thereto a tension rod 109 which, in turn, is connected with a moderate amount of lost motion to a crank arm 110 rigidly attached to the rockshaft 68. By the use of the foregoing arrangement, depression of the plunger 39 serves to rotate the rockshaft 68 counterclockwise through the necessary angle to disengage the switch actuating crank arm 66 thus insuring that the releasing switch 29 remain open. At the same time, the rockshaft 68 through the crank arm 111 and the floating lever 74 serves to draw the slideable master gate 61 to its extreme outward position (see Fig. 18). This opens all the coin accumulating chutes and any coins previously stored therein consequently drop into the dumping chamber 92. Since the dumping gate 95 at this time will not block off the chamber 92 from the coin return tray 94, the coins dropped from the chutes will be directed into the tray.

Rigidly secured to the rockshaft 108 and movable therewith are axially spaced wiping arms 111, each of the latter being adapted to strip magnetic slugs and the like from respective ones of the coin selectors 35a, 38a and 36a. Material of this sort, which is stripped when the plunger 39 is depressed, is spilled into the dumping chamber 92 along with the other coins being returned.

In order to prevent an individual with fraudulent intent from securing a return of his purchase money after the mechanism 20 has unlocked the machine 21 and steps have been taken to claim the purchase, an effective interlock is interposed between the unlocking mechanism of the machine 21 and the coin return linkage. (Refer to Figs. 1 and 10.) Thus the locking cam shaft 24 is provided with a large segmental cam 112 with a large, abrupt shoulder 113 in its contour. A rocker arm 115 having a perpendicular leg 116 at one end is mounted on a fixed supporting bracket in a manner which permits the leg 116 to ride along the shoulder 113 when the shaft 24 is in the locking position. The opposite end of the arm 115 is, of course, pivotally coupled to the coin return lever 107 by means of an adjustable link 118. With this construction, it will be appreciated that when the shaft 24 is rotated to its unlocked position, the curved portion of the cam 112 will ride over the leg 116, preventing

the rocking of the arm 115 and effectively locking out the coin return plunger 39.

OPERATION AT FIXED PREDETERMINED TOTAL VALUE

Using the exemplary total value of fourteen cents, the operation of the coin controlled mechanism 20 will be traced for each of the four possible coin combinations which add up to such total. These combinations are as follows: (a) all pennies; (b) two nickels and four pennies; (c) nine pennies and one nickel; (d) one dime and four pennies. During the course of the discussion, particular reference will be made to Figs. 15 to 23 inclusive.

(a) Combination all in pennies

The coins will travel from the penny slot 35 via the entry chute 35a and coin selector 35b to the funnel-like passage 51 of the penny director 49. Assume that all the coin accumulating chutes are empty and that their lower ends are blocked off by the master gate 61. Under such conditions, the arm 80 of the penny director will be in abutment with the highest stop dog 82 and the passage 51 will register with the innermost penny accumulating chute 35c1 admitting coins thereto. The first three pennies will then fill up the first branch of the chute 35c1 (see Fig. 5), with the fourth penny spilling over into the second branch of the chute. As the fourth penny descends, it depresses the tail bar of the stop dog 82, swinging the latter out of abutment with the arm 80 and allowing the penny director to rock through a small arc until the arm 80 is accosted by the next highest stop dog 83. This arc is represented by the distance $a-b$ in Fig. 19, constituting the first increment of step-by-step movement of the depending end of the penny director 49. As an incident to such movement, the floating lever 74 will fulcrum on the master gate as at point e , moving from a full line position $a-e$ to the first broken line position $b-e$. Consequently, the upstanding crank arm 71, the rockshaft 68, and the crank arm 66, are likewise rocked through the first of the three steps of arcuate movement required to close the releasing switch 29.

Having moved through the step described above, the penny director 49 has brought its passage 51 into registration with the next penny accumulating chute 35c2, admitting coins into the same. The first four pennies will fill the first branch of the chute, the fifth coin spilling over into the second branch thereof and depressing the tail bar of the stop dog 83. This serves to rock the latter out of engagement with the arm 80, permitting the same to drop down to the lowest dog 84. At the same time, the depending end of the penny director 49 shifts through the increment designated $b-c$ in Fig. 19, also shifting the floating lever 74 from position $b-e$ to position $c-e$. This shift results in moving the crank arms 71 and 66, together with their rockshaft 68, through the second step of arcuate movement toward the closing point for the switch 29.

At this point, the passage 51 has been brought into registration with the third penny accumulating chute 35c3 which receives the last five pennies of the fourteen cent combination. The fifth penny to enter this chute depresses the tail bar of the last dog 84 after the manner described in connection with the other dogs. The depending end of the penny director is accordingly shifted

through its third and last step, indicated at $c-d$ in Fig. 19. By the same token, the floating lever 74 is shifted from the position $c-e$ to the position $d-e$, simultaneously rotating the crank arm assembly and its rockshaft 68 through the third and last increment of arcuate movement. As a result, the crank arm 66 cams against the resilient actuating arm 65, closing the switch 29 and releasing the locking mechanism of the vending machine 21.

Under the foregoing circumstances, the deposited coinage, which totals fourteen cents, is retained in the coin accumulating chutes by the master gate 61, the latter occupying the relative position illustrated in Fig. 15. However, as soon as the customer elevates a delivery receptacle of the vending machine 21 to claim his purchase, an appropriate electrical circuit is completed and energizes the solenoid 30. This immediately results in the raising of the movable core 31 and the mechanical linkage (see Figs. 1 and 3) associated therewith, comprising a depending rod 119 adapted to lift actuating lever 120 of the coin dumping gate 95. The latter when so lifted swings the gate 95 to the broken line position shown in Fig. 9, blocking off the coin return tray and permitting communication between the dumping chamber 92 and the coin box 32. The lever 120 when lifted also serves to engage a crank arm 121 keyed or otherwise rigidly secured to the rockshaft 68. Consequently, the shaft 68 is rotated against the force of the spring 70 and counterclockwise as viewed from Fig. 3 to its extreme position, moving with it the upstanding crank arm 71, the floating lever 74, the depending end of the penny director 49, and the master gate 61. This brings the lever 74 to the position indicated by the broken line $x-y$ in Fig. 23 and at the same time moves the lower end of the penny director hard against its adjustable stop pin 125 (see Fig. 2). By the same token, the slidable master gate 61 is shifted from the position of Fig. 15 to that of Fig. 18, wherein an upstanding stop pin 122 on the gate 61 limits the latter's travel by engaging a finger 124 unitary with the swingable plate 44 and forcing such finger against the wall of the nearest coin chute. The stop screw 46 is also swung clear of the coin chute 35c1 in the process. When the gate 61 has reached the position shown in Fig. 18, its obstructing abutments have been moved clear of all coin accumulating chutes, dropping the coins therefrom into the dumping chamber 82 from which they pass into the coin box 32. As soon as the customer has claimed his purchase and allowed the delivery receptacle to return to its original position, the solenoid 30 becomes de-energized and allows the spring 70 to restore the counting mechanism to its initial condition for a repetition of the operating cycle.

(b) Combination of two nickels and four pennies

Assume now that the coin accumulating chutes are empty and that a nickel is deposited. The coin will enter the first branch of the nickel accumulating chute 36c where it will immediately depress the tail bar of the dog 85 (see Figs. 4 and 7). This will permit the master gate 61 to pass through the first increment of its step-by-step movement to occupy the position shown in Fig. 16, such movement being represented by the distance $e-f$ in Fig. 20. The floating lever 74 is also permitted to move through the first of its three switch closing steps to occupy the position $a-f$. Due to the engagement between the gate

61 and the depending finger 85 of the nickel diverter 83, the first branch of the chute 36c is now blocked off. A second nickel deposited at this point will spill over into the second branch of the chute 36c, releasing the second nickel dog 86 and allowing the master gate 61 to slide through its second step *f-g* to the position indicated in Fig. 17. The lever 74 likewise passes through its second increment of switch closing movement to the position *a-g* of Fig. 20. Under these conditions, the coin diverters block off completely the nickel chute 36c and the dime chute 38c, any subsequently deposited nickels or dimes being spilled by the diverters 96 and 98 into the coin return tray. If the four pennies required to complete the above combination be deposited, the last coin will serve to initiate movement of the penny director through the first step *a-b* after the manner already described, thus shifting the lever 74 through its third and last step to the position designated by the line *b-g* in Fig. 20. As a result, the switch 29 is energized, the accumulated coins are subsequently dumped into the coin box 32, and the counting mechanism returns to initial position all as heretofore explained.

(c) *Combination of nine pennies and one nickel*

In the light of the foregoing, a detailed discussion of the operation of the counting mechanism in response to the receipt of this combination seems unnecessary. However, it might be helpful to point out that the step sequence is indicated in Fig. 21. With the deposit of the first four pennies, the penny director moves through the step *a-b* and with the deposit of the next five, moves through the step *b-c*. If pennies in excess of this number be deposited, followed by the deposit of a nickel, the consequent shift of the gate 61 through step *e-f* will dump the extra pennies into the coin return tray and simultaneously result in closing of the switch 29.

(d) *One dime and four pennies*

In response to this combination, the counting mechanism behaves in a manner very similar to that employed in connection with combination (b), supra; the deposit of a dime merely serving to perform both nickel steps at the same time due to the simultaneous release of both nickel dogs 85 and 86 by depression of the tail bar 88. The sequence of steps is illustrated in Fig. 22, differing from that shown in Fig. 20 only to the extent that the gate 61 shifts through the distance *e-g* in a single move rather than two successive ones.

OPERATION AT VARIOUS PREDETERMINED TOTAL VALUES

As mentioned earlier in the specification, the mechanism 20 may be readily conditioned for response to the deposit of any combination of coins having any selected predetermined total value between one and fourteen cents. The operation of the mechanism at these various values, together with the adjustments involved in conditioning the latter to respond to such values, will be discussed briefly below.

(a) *Values from eleven to fourteen cents*

By locating the stop screw 46 in selected ones of the tapped holes in the swingable stop plate 44, the effective storage capacity of the first penny accumulating chute 35c1 may be altered to accommodate one, two, three, or four coins.

The step-by-step operation of the mechanism remains identical with that already described.

(b) *Value of ten cents*

This necessitates making the first penny accumulating chute 35c1 inactive, which can be readily done by securing the highest weighted dog 82 in a disengaged position through the use of a retainer spring 127. The step-by-step operation of the mechanism remains unchanged except for the fact that the latter behaves as if the first step of movement of the penny director 49 had already been completed.

(c) *Values of six to nine cents*

In this instance, the first nickel dog 85 and the dime dog lever 88 are removed or rendered inactive. The master gate 61 will then assume an initial position at a point where its first step of sliding movement has been completed. Any dimes then deposited will be returned by the diverter 98, while the first nickel deposited will be so directed by the nickel diverter 96 that such coin actuates the second nickel dog 86. Additional nickels then deposited will be returned. The penny chutes are conditioned by suitable positioning of stop screws 46 on the plate 44 to vary the storage capacity of the first accumulating chute 35c1. By latching up the middle dog 83, the penny distributor may be caused to shift directly from chute 35c1 to 35c3. Under the foregoing conditions, the switch 29 is closed by two steps of movement of the lever 74 and the parts associated therewith.

(d) *Value of five cents*

As in the case of (c), the first nickel dog 85 and the dime dog lever 88 are removed or rendered inactive, initially positioning master gate 61 as if it had completed its first step of sliding movement. In addition, both penny dogs 82 and 84 are latched in the disengaged condition, rendering the first two penny accumulating chutes 35c1 and 35c2 ineffective and positioning the penny director as if it had completed two increments of movement. With such an arrangement, the depositing of a nickel will serve to move the lever 74 through the one remaining step required to close the switch 29.

(e) *Values from one to four cents*

In this instance, both nickel dogs 85 and 86 are removed or rendered inactive and two penny dogs 82 and 83 are retained in the disengaged position. The first penny accumulating chute 35c1 will be the only active one and its capacity may be altered by adjusting the position of the stop screw 46 on the plate 44. Upon the filling of the penny chute 35c1, the lever will shift through its three switch closing steps in a single move. Any nickels, dimes, or excess pennies deposited with the mechanism as thus set up will be returned.

(f) *Other values*

While the embodiment of the mechanism described heretofore has been designed to handle pennies, nickels and dimes, the device could just as easily handle a series of coins of higher denomination such as nickels, quarters and half dollars.

I claim:

1. In a multiple coin controlled release mechanism for vending machines and the like, the combination comprising a frame, a plurality of coin accumulating chutes fixed to said frame and

adapted to receive coins of different denominations, each of said accumulating chutes except the one for the highest denomination coin having partition means therein dividing the chute into first and second branch chutes and arranged for the automatic diversion into the second branch chute of the last of a predetermined series of coins to enter the accumulating chute, a plurality of coin dogs pivoted on said frame, certain of said dogs having actuating means operatively associated therewith and extending into operative relation with said highest denomination accumulating chute for tripping said certain dogs in response to the depositing of a coin in said last mentioned chute, some of said dogs having means thereon extending into operative relation to respective ones of said second branch chutes to be tripped by coins received therein, a step-by-step coin counting mechanism including a floating lever having retaining means thereon disposed for engagement by said dogs, means on said lever for bodily moving the latter through a cumulative series of steps relative to said frame as respective ones of said coin dogs are tripped, a releasing switch, and switch actuating means connected to said lever for closing said switch in response to the bodily movement of said floating lever as the latter passes through the last of the cumulative series of steps.

2. In a multiple coin controlled release mechanism for vending machines and the like, the combination of a frame, a plurality of coin accumulating chutes fixed to said frame including a series of chutes fashioned to receive coins of the lowest denomination and at least one additional chute fashioned to receive coins of higher denomination, each of said accumulating chutes except the one for the highest denomination coin having partition means therein dividing the chute into first and second branch chutes and a passage between the branch chutes for the automatic diversion into the second branch chute of the last of a predetermined series of coins to enter the accumulating chute, a plurality of coin dogs pivoted on said frame, actuating means operatively associated with said highest denomination accumulating chute and at least one of said dogs for tripping the latter in response to the dropping of a coin into said last mentioned chute, a number of said dogs having coin responsive tripping means thereon extending into operative relation with respective ones of said second branch chutes, a slideable master gate disposed in abutment with the lower ends of said accumulating chutes and adapted to block off the latter, a rockable coin director pivoted on said frame and including a coin guide overlying said series of accumulating chutes for the lowest denomination coin, said coin director being shiftable in steps in response to the tripping of the remaining of said coin dogs, a floating lever pivotally connected at its respective extremities to said master gate and to said coin director, both of the latter being adapted to serve as shiftable fulcrums for said lever, biasing means interconnected with said gate and with said coin director for exerting biasing forces thereon, the ones of said dogs associated with said series of lowest denomination chutes being removably engagable with said director and the remainder of said dogs associated with said chutes other than those of said series being removably engagable with said gate, and means including a

rockable control member connected to said floating lever intermediate the extremities thereof and movable therewith as an incident to tripping of various ones of said dogs, a releasing device, and actuating means on said control member for actuating said releasing device upon movement of said control member.

3. In a multiple coin controlled release mechanism for vending machines and the like, the combination of a frame, a plurality of coin accumulating chutes fixed to said frame and including a series of chutes for receiving pennies and at least one additional chute for receiving coins of larger denomination, a plurality of coin dogs pivoted relative to said frame and disposed in projecting relation with said accumulating chutes for pennies, adjustable stop means interengageable with one of said penny accumulating chutes for varying the capacity thereof from one to four pennies as determined by the setting of said adjustable stop means, means interconnecting said dogs with said penny chutes for effecting the tripping of said coin dogs in response to the filling of said respective penny accumulating chutes to capacity, dogs operatively associated with said accumulating chutes other than said penny chutes, a releasing device, and counting means interengageable with said dogs for actuating said releasing device in response to the tripping of any combination of various ones of said dogs corresponding to a predetermined total value of coins.

4. In a vending machine, the combination of withdrawable article delivery means, a segmental cam pivotally mounted on said article delivery means, a locking device connected to said cam and extending into interengagement with said article delivery means for positively inducing pivotal movement of said cam upon attempted movement of said article delivery means, a multiple coin controlled release mechanism interconnected with said vending machine, a coin return mechanism on said coin controlled release mechanism, a coin return lever pivotally mounted on said machine and interconnected with said coin return mechanism, actuating means connected to said lever and operable from the exterior of said machine, a link pivotally connected at one end to said coin return lever, a rocker arm swivelly attached to the opposite end of said link and pivotally attached to said machine about an axis substantially parallel to the pivotal axis of said cam, and a leg unitary with said rocker arm and extending substantially parallel to the pivotal axis thereof for blocking rotation of said cam and thereby locking said article delivery means as an incident to actuation of said coin return lever, said locking device serving as an incident to actuation of said article delivery means to rotate said cam into motion-blocking relation to said leg, thus precluding actuation of said coin return lever.

5. In a multiple coin controlled release mechanism for unlocking a vending machine or the like upon the deposit therein of coinage, the combination comprising a plurality of coin accumulating chutes fashioned to receive coinage of various denominations, means overlying said accumulating chutes for channeling deposited coins therein, a floating member shiftable disposed in proximate relation to said chutes for incremental movement in a given direction, biasing means for urging said floating member in said given direction, an unlocking control member operatively associated with said floating member for actuation thereby

upon movement thereof in said given direction a predetermined distance, a plurality of dog elements projecting into respective ones of said accumulating chutes for interception of coins therein, means connecting said individual dog elements with said floating member for controlling the incremental movement thereof, a plurality of coin deflectors associated with respective ones of said chutes and disposed for interception of coins entering thereinto, and means connecting said floating member with said deflectors for actuation of the latter in response to incremental movement of the former.

6. In a multiple coin controlled release mechanism responsive to the deposit therein of coinage aggregating a predetermined total value, the combination of a plurality of coin accumulating chutes fashioned to receive coinage of different denominations and defining discharge ends thereon, adjusting means interengageable with certain ones of said accumulating chutes to selectively vary the coin accumulating capacity thereof, a movable coin entry director having a portion disposed in overlying relation with certain ones of said accumulating chutes, interconnecting means operatively associated with said certain ones of accumulating chutes and said director for conditioning the latter for shifting movement to succeeding ones of said last mentioned chutes in response to the receipt of coin therein, a movable gate disposed in proximity to said discharge ends of said accumulating chutes and adapted normally to obstruct the same, a floating lever having one end connected to said coin director and the other end connected to said gate, an unlocking control member susceptible of actuation by said floating lever and connected thereto intermediate the ends thereof, biasing means interconnected with said control member, a plurality of sequentially releasable coin dogs each having a portion projecting into one of said accumulating chutes other than said certain ones thereof and another portion engageable with said gate, means associated with said dogs and providing for selective inactivation thereof to vary the predetermined total value of coinage to which said mechanism is responsive, and a plurality of movable coin deflectors associated with respective ones

of said chutes and disposed for interception of coins entering thereinto, all but one of said deflectors having an operable connection with said gate, the remaining one of said deflectors having an operable connection with said coin director.

7. In a multiple coin controlled release mechanism of the character set forth, the combination of a plurality of coin accumulating chutes, a slideable gate disposed in underlying relation with said chutes for retaining coins therein, a rockable coin director associated with certain one of said chutes and adapted to channel coins thereinto, a floating lever connected at its extremities to said slideable gate and to said coin director, said lever being adapted to fulcrum on either said gate or said coin director, means including a control member and a biasing member connected to said floating lever intermediate the ends thereof, and a plurality of sequentially releasable coin actuated dogs each having a portion projecting into an associated one of said accumulating chutes other than said certain ones thereof and another portion engageable with said gate, another plurality of coin actuated dogs each having a portion thereof projecting into an associated one of certain chutes and another portion thereof engageable with said coin director, said dogs being adapted to release said gate and said coin director with selective step-by-step movements under the action of said biasing member, each of said step-by-step movements producing a substantially equal increment of movement of said control member regardless of whether said lever fulcrums on said gate or on said coin director.

WILHELM WELLSTEIN.
